[57] CLAIM

The ornamental design for a combined shelf and that hook unit, as shown and described.

DESCRIPTION

FIG. 1 is a top, front, and left side perspective view of a combined shelf and hook unit showing my new design;

FIG. 2 is an enlarged front elevational view thereof;
FIG. 3 is an enlarged right side elevational view thereof, the left side being a mirror image of that shown; and

FIG. 4 is an enlarged bottom plan view thereof.

FIG. 1

FIG. 2

FIG. 3

FIG. 4
